ATTORNEYS

UNITED STATES PATENT OFFICE.

THEODORE ROXBURY, OF BROOKLYN, NEW YORK.

ANCHOR FOR LOWER DENTURES.

Application filed August 4, 1923. Serial No. 655,597.

To all whom it may concern:

Be it known that I, THEODORE ROXBURY, a citizen of the United States, and a resident of the city of New York, borough of Brooklyn, in the county of Kings and State of New York, have invented certain new and useful Improvements in Anchors for Lower Dentures, of which the following is a full, clear, and exact description.

10 The present invention relates to anchors for dentures, and more particularly to anchors for holding the lower denture in operative position in the mouth by means causing the anchors to cling to the side walls 15 thereof, thereby preventing relative movement of the denture with respect to the lower jaw, but permitting freedom of movement of the same conjointly with the movement of the lower jaw.

20 It is a habit with many people when eating to bite on the forward incisors instead of grinding the food by means of the molars at the sides. This has a tendency of exerting a downward pressure on the forward 25 portion of the denture causing it to tilt at the rear and producing an alternate rising and falling of the rearward portion of the denture or a rocking of the denture during the eating process. With this in mind, an 30 object of the present invention is to produce an anchor for lower dentures which, while at all times permitting the denture to move freely with the movement of the lower jaw, shall nevertheless hold the denture sufficiently rigid to prevent rocking or tilting.

Another object in view is to provide an articulated anchor which permits a relatively large freedom of movement of the denture with the lower jaw, with little or no 40 movement of the anchor, and which in addition is flexible laterally permitting a slight lateral movement of the denture and allowing it to be readily positioned in the mouth or removed therefrom without discomfort or 45 injury to the tissues of the mouth.

Still another object in view is the provision of an anchor adapted to be secured one to each side portion of the denture having recessed members for engaging the recess or hollow in the side wall of the mouth at the rear of the cartilaginous ridge supporting the denture, the said recessed members being adapted to cling to the side walls of the mouth by suction means for the purpose 55 of holding the denture against relative movement with respect to the lower jaw.

A further object in view is the provision of means for holding the said recessed members in normal operative position against the side walls of the mouth.

60 The present invention is illustrated in the accompanying drawings, in which—

Fig. 1 is a perspective view showing a portion of a lower jaw supporting a denture and a pair of anchors applied to the denture 65 for holding the same in operative position thereon.

Fig. 2 is a horizontal sectional view on line 2—2 of Fig. 1.

Fig. 3 is a perspective view of a portion 70 of the anchor.

Fig. 4 is a top plan view of Fig. 3 illustrating a modified form of anchor.

Fig. 5 is a similar view of Fig. 3 showing 75 another modified form of anchor.

Referring to the drawings illustrating the invention, 1 indicates an anchor for a lower denture comprising a hard rubber block 2, to which is pivotally mounted one end of a spring bar 3 on a pivot pin 4. The opposite end of the bar 3 carries a member 5 recessed at 6 to form a vacuum cup 7. The recessed member 5 is formed of rubber composition having sufficient flexibility for the vacuum cup 7 to readily form a suction 85 with a side wall of the mouth for the purpose of holding the anchor in a relatively fixed position. When in operative position on the denture, the spring bar 3 operates to hold the vacuum cup 7 in contact with the 90 side wall of the mouth. The block 2 is adapted to be vulcanized to the denture 8 as at 9, but may be secured thereto by gold rivets or other preferred means.

95 As shown in Figure 1, the denture 8 comprising a set of false teeth for the lower jaw 10, is provided with a pair of the anchors 1 secured one to each side portion 11 thereof, one anchor being shown in full view, while a portion only of the other anchor is shown. The member 5, as shown in Figure 1, engages the side wall of the mouth in the hollow 12 at the rear of the cartilaginous ridge supporting the denture, thereby holding the denture against relative movement with respect to the lower jaw.

105 The spring bar 3 being flexible laterally permits a slight lateral movement of the denture and at the same time allows the denture to be positioned in the mouth or removed therefrom without discomfort or injury to the tissues of the mouth. The move-

ment of the denture afforded by the pivotal connection with the bar 3 may not be sufficient to permit the denture to move freely with the movement of the lower jaw in some individuals. For instance, it has been found that the lower jaw of certain individuals has a reciprocating movement in addition to the vertical chewing and grinding movement. To accommodate such movement of the lower jaw and to permit the denture to move freely therewith, the bar 3 shown in the modified form in Figure 5 is provided with a longitudinal slot 13 for engagement with the pin 4, thereby permitting the denture to move in a reciprocating manner with the lower jaw without relative movement of the anchor. Likewise in the modified form shown in Figure 4, the bar 3 is provided with a transverse slot 14. The pin 4 moving freely in the slot 14 permits a short vertical movement of the rearward portion of the denture, thereby preventing the denture binding the jaw of individuals accustomed to open their mouth wider than others.

It will be understood that the recessed member 5 clinging by suction to the side walls of the mouth as at 12, firmly holds the denture against rocking or tilting on the lower jaw 10. At the same time the flexibility of the bar 3 permits the denture a slight lateral movement, and being articulatively connected to the denture permits the

denture to move freely with every movement of the lower jaw.

Having described my invention, I now claim:

1. A denture provided with a bar member projecting rearwardly from one side portion thereof, said member having a recessed member secured thereto remote from the denture adapted to cling by suction to a side wall of the mouth.

2. An anchor for lower dentures comprising a recessed member adapted to cling by suction to a side wall of the mouth, a spring bar secured to said recessed member operating to hold said member in contact with the said side wall, and means articulatively connecting said bar to the denture.

3. The combination, with a lower denture, of a pair of anchors pivotally secured thereto, one on each side portion thereof, each comprising a bar member projecting rearwardly of the denture, and a cup-shaped member secured to the free end of said bar.

4. The combination, with a lower denture, of a pair of anchors pivotally secured thereto, one on each side portion thereof, each comprising a bar member provided with an aperture at its one end for pivotal engagement with the denture, and a suction member at the other end for engagement with the side wall of the mouth.

THEODORE ROXBURY.
